UNITED STATES PATENT OFFICE.

WILLIAM JAMES HERRON, OF WILKINSBURG, PENNSYLVANIA.

LOCKING THROTTLE-HANDLE FOR PNEUMATIC TOOLS.

1,203,735.

Specification of Letters Patent.

Patented Nov. 7, 1916.

Application filed January 17, 1916. Serial No. 72,541.

To all whom it may concern:

Be it known that I, WILLIAM J. HERRON, a citizen of the United States, residing at Wilkinsburg, in the county of Allegheny 5 and State of Pennsylvania, have invented a new and useful Locking Throttle-Handle for Pneumatic Tools, of which the following is a specification.

The present invention appertains to the 10 throttle handles of pneumatic tools, such as are used in structural work, and the like, and it is the object of the invention to provide a throttle handle which when released will serve to automatically close and lock 15 the valve, whereby to shut off the air or motive fluid, and to prevent the valve being accidentally opened when the handle is grasped for lifting or manipulating the tool unless the handle is manipulated in a predetermined manner for opening the valve.

It is not infrequently the case, with the 20 use of ordinary throttle handles, that the tool in being accidentally dropped will continue to operate, due to the failure of the 25 valve to close, which is objectionable since the tool in continuing to operate is liable to produce injuries or accidents. Again, with an ordinary throttle handle, it is necessary to carefully lift the tool by the handle, 30 since if the tool is carelessly or negligently handled by the handle, the weight of the tool is apt to cause the valve to be unseated prematurely, thereby starting the tool before it should, and rendering it possible for the 35 tool to produce mishaps, which are avoided by the present invention, since it is not possible with the present handle to unseat the valve prematurely simply by raising or otherwise manipulating the tool by grasping 40 the handle, it being necessary to manipulate the handle in a predetermined manner for unseating the valve, but this can be done in a convenient and unobjectionable manner.

It is also within the scope of the invention 45 to provide a locking throttle handle for pneumatic tools, which is comparatively simple, non-encumbering and inexpensive in construction, which is not apt to become clogged up in use, and which will serve its 50 office in a thoroughly reliable, satisfactory and efficient manner.

With the foregoing and other objects in view which will appear as the description 55 proceeds, the invention resides in the combination and arrangement of parts and in the details of construction hereinafter de-

scribed and claimed, it being understood that changes in the precise embodiment of the invention herein disclosed can be made within the scope of what is claimed without departing from the spirit of the invention.

The invention is illustrated in the accompanying drawings, wherein:

Figure 1 is a longitudinal section of one form of throttle handle. Fig. 2 is an elevation of the tubular casing or shell. Fig. 3 is an elevation of the valve operating sleeve. Fig. 4 is an elevation of a modified form of valve casing or shell. Fig. 5 is a longitudinal section of a modified form of throttle 70 handle employing the casing illustrated in Fig. 4. Fig. 6 is a longitudinal section of another variation. Figs. 7, 8 and 9 are enlarged cross sections taken on the respective lines 7—7, 8—8 and 9—9 of Fig. 6. Fig. 10 75 is a fragmental elevation of the valve casing of the third form illustrating the cam opening therein.

In carrying out the invention, reference being had to Figs. 1, 2 and 3 wherein the first form of the invention is depicted, there is provided a tubular valve casing or barrel forming the handle for manipulating the tool, one end of the casing 1 being enlarged and interiorly threaded, as at 2, for the attachment of the drill or other tool (not shown). The enlarged end 2 provides the shoulder 3. Attached to the other end of the casing 1 is a hose connection or coupling 4, for the attachment of the air or pressure 90 fluid hose, as usual, the connection 4 having a nipple 5 threaded or otherwise engaged in the end of the casing 1, and providing a shoulder 6 facing the shoulder 3. The casing 1 thus provides means for connecting the 95 hose and tool, and also acts as a handle whereby the tool can be conveniently manipulated.

In order to control the flow of air or motive fluid through the casing 1, said casing 100 is provided between its ends with a valve seat 7 against which a frusto-conical valve 8 is seatable in the direction of the flow of fluid through the casing, whereby the valve 8 will close automatically by the pressure 105 of the fluid if the valve is free to be seated. The valve 8 has an axial stem 9 projecting to opposite sides of the valve, one terminal of the stem 9 being slidable through a guide 10 engaged within the casing 1 adjacent the 110 connection 4, and provided with apertures or openings 11 for the flow of fluid there-

through without interference. A coiled wire expansion spring 12 is disposed upon the stem 9 between the valve 8 and guide 10, and has a tendency to seat the valve 8.

- 5 In order to provide means for unseating the valve, which must be done against the pressure of the motive fluid, a cylindrical plunger 13 is slidably snugly within the casing 1 in front of the valve seat 7, and is provided with a bore 14 extending from its forward end to a point adjacent its rear end, the rear end of said plunger 13 having diverging apertures 15 extending from the respective end of the bore 14 to permit the motive fluid to flow from the valve seat through the apertures 15 into the bore 14, and from there to the tool. The rear end of the plunger 13 has a central finger or stud 16 projecting therefrom in alignment with the stem 9 and normally spaced from said stem, but adapted to contact with the forward end of said stem when the plunger 13 is moved rearwardly, it requiring a short movement of the plunger before the finger 16 engages the valve stem, so that the further movement of the plunger will unseat the valve. A coiled wire expansion spring 17 is confined between the valve 8 and rear end of the plunger 13, being held in place upon the finger 16 and valve stem 9, whereby said spring tends to separate the valve and plunger, the spring 12 normally overcoming the tension of the spring 17 to seat the valve 8.
- 35 In order to operate the plunger 13 from the exterior, a sleeve 18 is mounted for rotation upon the casing 1 and has its ends abutting the shoulders 3-6 to prevent the endwise movement of the sleeve. The casing 1 is provided with a longitudinal slot 19 between the plunger 13 and sleeve 18, and the sleeve 18 is provided with a coöperating oblique cam slot 20 having its forward end extended longitudinally, as at 21, to provide a shoulder 22. A pin 23 has an inner reduced threaded end 24 threaded into the plunger 13, and said pin 23 works longitudinally within the slot 19 of the casing 1. This pin also projects through the slot 20, and is provided at its outer end with an enlarged thumb or finger piece 25. The thumb piece 25 and sleeve 18 are preferably knurled, to prevent slipping when they are operated by the hand.
- 55 When the sleeve 18 is released, the plunger 13 is forced forwardly under the influence of the spring 17, thereby moving the pin 23 forwardly to the forward end of the slot 19, the pin 23 in being moved forwardly within the slot 20 rotating the sleeve 18 to initial position, and the pin 23 entering the longitudinally extending terminal 21 of the slot 20 to rest behind the shoulder 22. Should the handle be grasped 65 to raise the tool with the tool so positioned,

that it has a tendency to rotate in such a direction as to carry the pin 23 along the slot 20, this movement of the pin 23 is avoided, since it rests against the shoulder 22, and there is therefore no possibility 70 of the plunger 13 being forced rearwardly accidentally to unseat the valve. The valve is thus not only seated automatically under the influence of the spring, when the sleeve 18 is released, but the device is also locked 75 to prevent the accidental opening of the valve, which are important and novel features of a device of the present character. To open or unseat the valve, the hand which grasps the handle is arranged with the thumb 80 or one finger upon the thumb piece 25, whereby said thumb piece can be readily moved rearwardly slightly to remove the pin 23 from the shoulder 22, and the sleeve 18 can then be rotated for forcing the pin 85 23 rearwardly due to the fact that the pin 23 works within the cam slot 20. When the sleeve 18 is so rotated, the pin 23 is forced rearwardly, to move the plunger 13 rearwardly, and the finger 16 in abutting 90 against the valve stem 9 will then unseat the valve 8. It is evident that the plunger 13 can be moved rearwardly slightly to move the pin 23 from the shoulder 22, since the finger is normally spaced from the valve 95 stem 9, which allows the free rearward movement of the plunger 13 without the necessity of starting the unseating of the valve 8, until after the sleeve 18 can be rotated for forcing the pin 23 rearwardly by 100 the cam action.

In the modification depicted in Figs. 4 and 5, the parts 1' to 18', inclusive, resemble the similarly numbered parts of the first form, the reference characters in Figs. 4 and 5 being primed, so that a reiteration will not be necessary. In this case, however, the sleeve 18' is mounted for limited longitudinal sliding movement between the shoulders 3' and 6', and the ends of the sleeve have annular flanges or lips 18^a overlapping the enlarged end 2' and connection 4' to close the spaces between the shoulders and ends of the sleeve. The chief difference resides in the manner of operatively connecting the plunger 13' and sleeve 18'. Thus, the sleeve 18' has an aperture 19', while the casing 1' has a coöperating oblique cam slot 20' whose forward end is extended longitudinally, as at 21', to provide the shoulder 22'. A pin 23' fitted snugly within the aperture 19' extends through the slot 20' and has its inner end threadedly engaging, as at 24', the plunger 13'. The plunger 13' being normally forced forward under the influence of the spring 17', will move the pin 23' into the forward terminal 21' of the slot 20' behind the shoulder 22', whereby the sleeve 18' cannot be rotated accidentally. In this case, the cam 115 120 125 130 135

slot is in the casing instead of the sleeve, as in the first form, but the same results are accomplished. To unseat the valve, it is necessary to slide the sleeve 18' rearwardly, thus moving the pin 23' away from the shoulder 22', and the sleeve 18' can then be rotated for moving the pin 23' along the cam slot 20', to thus force the plunger 13' rearwardly for oscillating the valve. It is to be noted that when the pin 23' is moved rearwardly from the shoulder 22' by the rearward movement of the sleeve 18', the plunger 13' moves rearwardly without unseating the valve, until the finger 16' contacts with the valve stem 9'.
Coming to the variation illustrated in Figs. 6 to 10, inclusive, this variation embodies the same general construction above described, and also has additional features.

There is a tubular valve casing 1" provided with an enlarged end 2" for the attachment of the drill or other pneumatic tool, the casing 1" having a shoulder 3", while the hose connection 4" which has the nipple 5" engaged with the other end of the casing 1" has a shoulder 6". The parts designated 7" to 18", inclusive, resemble the similarly numbered parts above described, and will be readily understood from the foregoing without a reiteration being necessary. The sleeve 18" is mounted for limited longitudinal movement between the shoulders 3" and 6", the same as in the second form, and has terminal flanges 18^b overlapping the casing 1" and connection 4" beyond the shoulders thereof. The sleeve 18" has an aperture 19", while the casing 1" has a cam opening 20", which may also be denominated a slot if necessary to correspond with the cam slots of the first two forms. This opening 20" is of approximate triangular contour, to provide diverging cam edges 20^b, the forwardly and longitudinally extending terminal or notch 21" between the adjacent ends of said cam edges 20^b providing the opposite shoulders 22". A pin 23" threadedly engaged, as at 24", to the plunger 13" projects through the opening 20" and into the aperture 19" whereby the pin 23" moves with the sleeve 18", and the plunger 13" is movable with the pin 23". When the sleeve 18" is released, it is moved forwardly by the spring 17" since the plunger 13" and sleeve 18" move together, and the pin 23" will therefore be forced along one or the other of the cam edges 20^b into the notch 21". The sleeve 18" cannot rotate accidentally for unseating the valve, since the pin 23" is held between the shoulders 22", and cannot turn in either direction unless the sleeve is moved rearwardly. To unseat the valve, the sleeve 18" is moved rearwardly to move the pin 23" away from the shoulders 22", and the sleeve can then be rotated in either direction to move the pin 23" against one or the other of the cam edges 20^b thereby forcing the plunger 13" rearwardly to unseat the valve, it being noted that the plunger has a short free rearward movement before unseating the valve to allow the pin 23" to be easily removed from the shoulders 22".
The provision of the opening 20" is of importance, since it enables the sleeve 18" to be rotated in opposite directions for reversing the tool, as will presently appear. The end 2" of the casing 1" is provided with a pair of outlet ports 26 one of which communicates with one side of the tool and the other of which communicates with the other side of the tool, whereby when air is delivered to one port 26, the tool is operated in one direction, and when air is delivered to the other port 26, the tool is operated in the opposite direction. To properly control the flow of air to either of the ports 26, a rotary frusto-conical or tapered valve 27 is mounted snugly within the end 2" of the casing, and is provided with a passage 28 adapted to be moved into registration with either of the ports 26 when the valve 27 is oscillated. The valve 27 is connected to the sleeve 18" whereby the sleeve 18" can be used for operating the valve 27. Mounted for rotation within the casing 1" between the valve 27 and plunger 13" is a coupling 29 slidably connected, as at 30, with the valve 27 and plunger 13", whereby said plunger, coupling and valve 27 rotate together. The coupling 29 has a bore or passage 31 establishing communication between the bore 14" and passage 28. The plunger 13" can thus be reciprocated without disconnecting it from the coupling 29, and at any position of the plunger 13", the valve 27 will be rotated with said plunger. Consequently, when the sleeve 18" is moved rearwardly to remove the pin 23" from the shoulders 22", the passage 28 ordinarily being disposed midway between the ports 26, so that the passage 28 and ports 26 are closed, the sleeve 18" can be rotated in either direction for bringing the passage 28 into registration with the desired port 26, to rotate the tool in the corresponding direction. The operator by manipulating the sleeve 18" can thus not only unseat the valve 8" in an effective manner, but can also operate the valve 27 for bringing it into position to rotate the tool in either direction.
From the foregoing, taken in connection with the drawings, the advantages and attributes of the several forms of the invention will be understood, it being noted that the several forms have common features, as well as specific ones.
Having thus described the invention, what is claimed as new is:

1. A throttle handle embodying a tubular valve casing, a sleeve rotatable thereon, one

of said parts having a cam slot with its forward end provided with a shoulder, a pin engaged with the other part and extending through said slot to normally move behind said shoulder, a normally seated valve in said casing, and a plunger slidable within the casing for unseating the valve, said plunger having a limited movement with respect to the valve before the valve is unseated, and said pin being secured to said plunger.

2. A throttle handle embodying a tubular valve casing, a sleeve rotatable thereon, one of said parts having a cam slot with its forward end provided with a shoulder, a pin engaged with the other part and extending through said slot to normally move behind said shoulder, a valve member within the casing, a plunger slidable within the casing for unseating said valve member, said pin being attached to said plunger, and a spring between the plunger and valve member for separating them.

3. A throttle handle embodying a tubular valve casing, a sleeve rotatable thereon, one

of said parts having a cam slot with its forward end provided with a shoulder, a pin engaged with the other part and extending through said slot to normally move behind said shoulder, said casing having a valve seat, a valve seatable against said seat and having a stem, a plunger slidable within the casing and having a finger at one end to abut against said stem, the plunger having a bore extending from its other end to a point adjacent the first mentioned end and an aperture extending from said bore at one side of said finger, said pin being engaged with said plunger, and a coiled wire expansion spring between said valve and plunger upon said finger and stem.

In testimony that I claim the foregoing as my own, I have hereto affixed my signature in the presence of two witnesses.

WILLIAM JAMES HERRON.
